UNITED STATES PATENT OFFICE.

GEORGE E. FOX, OF CHICAGO, ILLINOIS.

DESK ACCESSORY.

1,410,668.

Specification of Letters Patent. Patented Mar. 28, 1922.

Application filed December 22, 1920. Serial No. 432,438.

To all whom it may concern:

Be it known that I, GEORGE E. FOX, a citizen of the United States, residing at Chicago, in the county of Cook and State 5 of Illinois, have invented new and useful Improvements in Desk Accessories, of which the following is a specification.

This invention relates in general to office equipment, and more particularly to an article designed primarily for desk use, but 10 also adapted to be used as a portable file, which can be folded up and readily transported with the work contained therein.

One of the primary purposes of this invention is to provide an article which will 15 be adapted to lie flat upon a desk surface and afford a work space covered by a blotter so that this portion of the article performs the function of a blotter pad, or, if preferred, it may have a glass surface, beneath 20 which desired data may be inserted and retained, exposed to view, and which will also afford upon either side of the work space a work distributor in which correspondence 25 and other papers and desk work may be filed so that they are readily accessible, but at the same time, concealed from the view of visitors, customers or clients. The work space or body portion and the distributors are hinged together and so proportioned 30 that the distributors may be folded over upon the body portion, thereby enclosing between them the work in the distributors and that lying on the body portion and providing a convenient file which 35 may be picked up from the desk and carried bodily with the work therein to a vault, another desk, or any place to which it may be desirable to convey the file and the data 40 contained therein.

Another object of the invention is to provide a desk accessory of the character indicated, which will be convenient for the user, and will be attractive in appearance 45 and durable in use.

Other objects and advantages of the invention will be readily appreciated as the same becomes better understood by reference to the following description, when 50 considered in connection with the accompanying drawings.

Referring to the drawings:

Fig. 1 is a plan view of an article embodying my invention when opened out and 55 laid flat on a desk in working position;

Fig. 2 is an end view of the article shown in Fig. 1 with the distributors folded over into closed position for transport;

Fig. 3 is a sectional view on the line 3—3 of Fig. 1;

Fig. 4 is a fragmentary enlarged view of one of the index card holders on a distributor leaf; and

Fig. 5 is a sectional view on the line 5—5 of Fig. 4.

Referring now to the drawings more in detail, reference character 6 indicates generally the body portion of the article which is shaped and proportioned to approximately the size of a standard desk blotter pad. This portion comprises a ply 7 of stiff material, such as heavy cardboard, to the rear or bottom face of which is secured a ply 8 of leather, pantasote, or other durable and attractive material, and upon the outer face of this ply is secured a facing ply 9 of felt, presenting a soft surface which will not mar the desk upon which the article is placed. The upper face of this central portion is also covered with a ply of material 70 11, preferably similar to the ply 8, and at each corner, there is provided a triangular tab 12, forming a pocket, beneath which the corners of a blotter 13 may be inserted, 75 thus providing a desirable working surface, capable of performing the function of a desk blotter. If preferred, however, a glass plate may be employed in lieu of a blotter, thus providing also a desirable working surface and serving to retain in position cards 80 or sheets bearing data, which are exposed to view through the glass where they may be quickly read at any time by the user.

At each side of the body portion, there is disposed a work distributor, indicated generally by reference character 13. Each distributor comprises a ply 14 of stiff material, similar to the ply 7, and the plies 8 and 11 are continued over the faces of the distributor plies 14, thus covering the same, 90 and forming at 15 a flexible hinge connection between the distributors and the body portion.

Each distributor comprises a series of leaves 16, hinged at their upper ends at different points to the stiff ply 14, as indicated at 17, so that the lower end of each is exposed beneath the next overlying leaf. These distributor leaves are adapted to receive between them correspondence or pa- 105 110

pers and other desk work, which the user may desire to have in convenient position, but in classified relation.

For the purpose of indexing these leaves 5 to facilitate temporary filing of the correspondence and other work in the distributors, each leaf is provided at its lower end with an index card holder, comprising a strip of relatively stiff sheet metal 18, folded over the lower edge of the sheet, the ends 10 of the metal being bent back upon themselves, as indicated at 19 and 21, to retain a sheet of celluloid or other transparent material 22, the ends of which are engaged beneath the folded ends 19 and 21 of the metal. From Fig. 5, it will be observed that the length of the transparent sheet is such that the forward or exposed portion thereof is disposed in spaced relation to the underlying metal, providing a slot or recess 23 15 into which a paper index card may be slipped longitudinally and held in exposed position, where it may be readily observed.

When in use on a desk, the article is laid 20 flat, as illustrated in Fig. 1, leaving the body portion exposed, as a working surface, and the two distributors in convenient position at either side of the working surface to hold correspondence and other matter which 25 may be placed therein. Should the user desire to leave his work without having it exposed to view, the distributors may be simply folded over onto the body portion, as shown in Fig. 2, thus enclosing not only the 30 work contained in the distributors themselves, but also that lying on the working surface. Furthermore, when the article is closed up in this manner, it may be readily carried about, or transported from place to 35 place, wherever the user may desire, and the work contained therein is protected, and when the device is opened out again, the work is exposed in convenient position to the user.

40 While I have shown and described a preferred embodiment of my invention, it will

be apparent that it is capable of considerable modification in its details of construction, and that in some instances, instead of employing two distributors, one only may be 50 attached to the body portion, which may be proportioned so as to be covered by the single distributor when folded over, or a portion of the working surface may be left exposed, when the device is closed up, depending upon the relative size and proportions of the parts. 55

I claim:

1. A desk accessory, comprising a central body portion and side portions hinged to 60 opposite side edges of said central portion, all of said portions when open being adapted to lie flat upon a desk and provide a flat central work surface flanked by said side portions, each side portion being provided 65 with leaves hingedly attached at their upper ends to their respective side portions to provide work distributors at each side of said work surface for the temporary reception of office work, said side portions with 70 the distributors thereon being adapted to be folded over onto said central portion to enclose work disposed on said work surface or in said distributors.

2. A desk accessory comprising a flat body 75 adapted to provide a work surface, and work distributors hinged to opposite side edges of said body and adapted when open to lie flat upon a desk, each of said distributors comprising a flat relatively inflexible backing hingedly connected to the body portion, each backing being substantially one-half 80 the width of said body portion, and leaves attached at the upper edge of each backing so as to open upwardly away from the user 85 of the device, said leaves being adapted to receive between them work which is to be temporarily filed, said distributors being adapted to be folded over onto said central portion to thereby enclose the work in said 90 distributors.

GEORGE E. FOX.
